UNITED STATES PATENT OFFICE.

JONAS GROSSNICKLE, OF NORTH MANCHESTER, INDIANA.

SILO.

1,314,644.

Specification of Letters Patent.

Patented Sept. 2, 1919.

Application filed January 24, 1919. Serial No. 272,916.

To all whom it may concern:

Be it known that I, JONAS GROSSNICKLE, a citizen of the United States, residing at North Manchester, in the county of Wabash 5 and State of Indiana, have invented certain new and useful Improvements in Silos, of which the following is a specification, reference being had therein to the accompanying drawing.

10 This invention relates to an improved silo and to improvements in the structural elements assembled to form the silo, these elements being the door frame parts, the staves, etc., molded from concrete.

15 In the drawings,

Figure 1 is a side elevation of a silo constructed with parts embodying my improvements.

Fig. 2 is a perspective showing one of the 20 main staves partly broken away.

Fig. 3 is a perspective of one of the shorter lower stay sections.

Fig. 4 is a vertical section showing one of the lower staves and a part of the one above 25 it.

Fig. 5 is a horizontal section on the line 5—5 of Fig. 1.

Fig. 6 shows two of the adjacent staves of a vertical series when one of them is mis- 30 alined.

Fig. 7 is a front view of the elements of a door assembled.

Fig. 8 is a vertical section on the line 8—8 of Fig. 7.

35 Fig. 9 is a horizontal section on the line 9—9 of Fig. 7.

Fig. 10 is a horizontal section on the line 10—10 of Fig. 7.

Fig. 11 shows on an enlarged scale the 40 parts in the lower portion of Fig. 5.

Fig. 12 is a vertical section on the line 12—12 of Fig. 1.

Fig. 13 is a perspective view of the elements surrounding a doorway, detached.

45 Fig. 14 is an elevation of part of the silo shown on an enlarged scale.

Fig. 15 is a partial horizontal section showing the adjacent parts of two staves on a scale approximating full size.

50 Figs. 16 and 17 are diagrams to illustrate, by contrast, characteristics of my improved stave.

In the drawings a foundation is indicated at 1, 2; this being formed of concrete and 55 shaped so as to have the bottom support lines of the staves all lie in the same horizontal

plane as nearly as possible. The upper elements of the structure are put in position upon the element 2 of the foundation before the components of the concrete have hardened or "set". The principal elements of the structure are those by which the doorways are surrounded and several series of uniformly sized and similarly shaped staves, together with sets of staves (for the bottom tier and the top tier) which are somewhat different in shape and size from those first referred to.

10, 10 indicate the staves for the larger part of the silo and are similar in shape and size. 9, 9 indicate staves which are approximately the same in length as those at 10, but at one end each is formed with a square edge. 11, 11 indicate shorter staves, each about one-half the length of the staves 10 75 and each at one end being square.

The main staves 10, 10, are shown as having flat inner and convex outer surfaces. One end edge of each is convex, being curved on the arc of a circle of long radius, as shown 80 at 14, and the curve extending continuously from the straight vertical lines of one side edge to the vertical lines of the other side edge. This convex end edge 14 is also rounded or curved, as shown at 15, in such 85 way that in each plane of intersection perpendicular to the planes of the side faces of the stave the edge line is seen as the arc of a circle of relatively small diameter. The opposite end edge is concaved, as shown at 90 16, the curvature at this edge being the relatively long arc of a circle of long diameter, similar to the arc of the convex edge 14. This end edge 16 is, as shown at 17, grooved or concaved in such a way that in each 95 plane of intersection through the flat sides of the stave the curved line at the edge is the arc of a relatively short circle conforming to that of the rounded edge at the convex end 15.

One of the vertical edges 19, 20 of each stave is formed with a longitudinally extending groove, as at 18, this conforming to the surface of a cylinder of short diameter. And the opposite vertical edge 20 is convex 105 or rounded to conform to the surface of a similar cylinder.

The staves 9, 9 are similar to those at 10, just described, except that the lower end edge 18 is flat and at right angles to the side edges 19 and 20 (see Figs. 1 and 4). The shorter staves 11, 11 are formed similarly

to those at 9, except that they are about one-half the length. There is a series of doorways 3, 3^a, 3^b, 3^c, etc., arranged one above another. The frame elements for each doorway are formed separately and comprise the bottom piece or sill bar 4, the vertical side bars 5, 6, and the top bar 7, Fig. 13. These are formed of concrete. The bottom and top bars are similar, each being formed with a main body part and with rib projections 8, one at each end. The side piece 5 of the door frame has face surfaces 21, 22. The outer edge 23 is convex, conforming to a part of the surface of a cylinder of a radius equal to that of the groove 13 at the edge of a stave. The inner side edge 24 is flat except at the ends where it is provided with short cavities 25, the surface of each of which also conforms to the cylinder specified. The other side element 6 of the door frame is similar to that at 5 except that its outer edge 26 has a cylindrical groove 27 instead of being convex; it also having at the upper ends of its inner vertical edge parti-cylindrical cavities 25. The parti-cylindrical ribs 8 on the top and bottom pieces 4 and 7 fit snugly into the parti-cylindrical cavities 25 in the side elements 5 and 6. The convex edge 23 of the door frame element 5 fits into the concave edge of any of the staves that may be placed adjacent to it. And, similarly, as to the concave groove 27 in the edge 26: it can be fitted snugly to the convex edge of any adjacent stave.

The door plate 28 is fitted into rabbets 29 formed along the edges of the top, bottom and side elements of the door frame.

The steps followed in assembling the elements of a silo, such as have been described, will be readily understood. The elements 4, 5, 6, 7 of a door frame are laid upon the concrete of the foundation floor 2 before it is finally hardened or set, the sill element being positioned as nearly as possible in a horizontal plane, and the side elements 5 and 6 being positioned vertically. Then a stave 9 is fitted tightly to the side element of the door with its flat bottom edge 18 horizontal. Then this is followed by putting in position one of the shorter staves 11, as shown in Fig. 1; followed by positioning alternately staves 9 and 11 around the entire circle of the bottom tier. Then a hoop or clamping band 30 is placed around the upper ends of the staves 9 and drawn somewhat tightly to position. The desideratum is to clamp together, and maintain in tight fit and in vertical positions, the long and short staves of the lower tier, the tension of the band being utilized to bring the groove edge 19 of each stave into a snug contact fit with the tongue or rounded edge 20 of its next neighbor. After the staves of lower tier have been assembled and clamped, the elements of the doorway frame 3^a are immediately put in

position above the lowermost door 3. Now use is made of the staves 10. They are slipped vertically into position. Their top edges will lie in different vertical planes, the lower and shorter bottom staves 9 and 11 causing the "breaking of joint" in the superposed tiers or staves. After those of each tier are assembled a supplemental band or clamping ring is applied as at 30^a.

The above procedure is repeated until a silo of the desired height is formed. At the top longer and shorter end staves 9 and 11 are used to insure that the upper end edges of all the vertical series of staves shall lie in a horizontal plane.

In order to greatly increase the strength of the concrete staves and the concrete elements of the doorway frame, I mold into them metallic reinforcing bars or strips 32. These are shown in Figs. 7, 8 and 9, and also shown in section in Figs. 2, 4, 11 and 12. They greatly increase the resistance of the concrete elements to fracture, and insure that powerful compression strains can be exerted without their being broken.

A matter of importance is the construction of the elements of the doorway frame as shown in Fig. 13, and others. These frames can be molded easily and, notwithstanding the weight of an entire door frame, it can be packed and transported easily and without danger of breakage when made in several elements in comparison with those made in integral structures. And this method is particularly advantageous in that the elements can be shifted more or less in respect to each other and yet maintain a liquid-tight joint without cracking or breaking. Under the powerful pressure exerted by the threaded rods of the clamping bands, the horizontal elements and the vertical elements of the doorway frame can adjust themselves to the lines of force and insure perfectly tight joints.

The conformations of the top and bottom edges 15 and 16 of the staves which I have devised are also of great importance. It will be seen that no stave has any part of the end edge (which contacts with the end edge of an adjacent stave) that is rectilineal; but that each stave-contacting edge is, throughout, struck as a part of the circle from a center positioned at a point in the central longitudinal line parallel to the long side edges. This parti-circular curved edge has no projection extending beyond the curvature of the edge, or any socket lying inside of such curvature or shoulder, interrupting the curvature. Hence there is no projection at the end of a stave to engage with a corresponding projection, or engage with a socket, on the next stave, either the one vertically above it or the one vertically below it. Consequently the edge surface at the curved end of any stave can slip in cir-

cular paths, to the right, or to the left, while contacting with the surface of the curved edge of the next stave, and the stave can, as an entirety, bodily move from left to right in curvilinear paths which are arcs of circles around the center point (above defined) on the next stave, without positively engaging with, or striking against, projections on said next stave.

At the same time I provide means for locking each stave against movement, transversely, bodily, of either of its end portions in relation to the end portion of the stave next adjacent. This locking is effected by the convex end portion of one stave being seated in the concave end portion of the next, and locking the end of one stave to the end of the next against horizontal rectilineal movement, or a movement bodily, laterally, relieves the staves to a great extent from the breakage strains incident to forces acting torsionally upon, or to twist, one part of the silo structure, above any given horizontal plane in relation to the other part below such plane. This bracing of the end part of one stave by the end part of the next stave has been heretofore attained by shaping the mutually contacting end edges so that they positively interlock, transversely, and prevent any lateral movement, bodily, of one in relation to the other, but I provide such interlocking, and, at the same time, permit movement bodily of the end part of one in relation to the contacting end part of the other.

As illustrated in Fig. 6, if any stave, such as that at 9^a in said figure, in the lower horizontal course, should not be initially brought to a correct position, or should become "set" in a position which is incorrect, in relation to the foundation (and consequently in relation to the door frame or to staves in that bottom course) or if a stave in any other course should be incorrectly positioned as to the staves therein, its longitudinal lines will be out of perfect parallelism with the longitudinal lines of adjacent staves. But the next stave above it, as at 10^a, can slip in a circular path laterally, while still having a fit therewith at their connecting ends. In Fig. 6 this misfit is exaggerated for the purpose of illustration.

The staves are thirty inches (or thereabout) in length; ten inches in width; and two inches (or thereabout) in thickness. The depth of the various grooves 13, 25, 27, etc., are from one fourth to one half of an inch in depth. In practical experience the misfits are not so great as to bring any portion of the extreme edge of the convex part 12 entirely away, laterally, from its companion groove 13, but a misfit to the extent of one sixteenth of an inch is serious. That is to say, the convex edge 12 may project into the groove 13 to the distance of one,

two or three sixteenths of an inch, and still have a serious misfit. Such misfits result with staves of the lower course from an erroneous fitting to the concrete at the bottom, or they may be caused by grains of sand or small, foreign particles getting into the grooves 13. When such misfitting of a stave occurs (that is to say, when it tends to be positioned so as to have its longitudinal lines inclined so as to be one, two or three sixteenths of an inch out of the vertical, but still have its vertical edges more or less overlapped by the edge parts of the laterally adjacent staves), the error in the fitting can be taken up by gradually distributing it over a greater or less area of the wall. It is preferable not to force together the staves that are in or adjacent a region of slight misfitting, but to draw them so that they will mutually distribute the misfit without any stave having any part of either edge forced out from the position of overlap in relation to the edges of the adjacent staves. When the ends have circular curves such as I have designed, the vertical pressure strains (transmitted from superincumbent weight downward along the vertical tiers, respectively), are distributed over the entireties of those ends, there being no narrow or easily breakable projections so positioned as to receive such strains. Of course it is not possible to eliminate absolutely all error of fitting. For instance, if a stave, as at 9^a, Fig. 6, in the bottom course, should be rigidly set one or three sixteenths of an inch out of vertical line, the best that can be attained is the distributing of the error throughout a region in such a way that at no part of a vertical edge will there be a loss of overlap. Then, to insure a liquid-tight seam at the edges of the staves, even where there is a misfitting to the extent of one or two sixteenths of an inch, I form grooves 35 (Fig. 15) at the inner corners of the edges 12 and 13. When the various, initially separate, elements of the silo have been assembled and clamped together the interior surface is covered with a film 36 of concrete, and either at this time or by a separate operation a seaming mass of concrete is forced into the grooves 25, and tight sealing is accomplished of the companion convex and concave surfaces 12 and 13 of the horizontally adjacent staves. The edge walls 37 of the sealing grooves are somewhat inclined to each other and serve to positively hold the sealing strip 38 of the cement in fluid-tight relation to the joint between the staves, and where there is a misfit such as has been referred to, the cement enters any crevices and forms a tight closure.

Figs. 16 and 17 are diagrams illustrating, by contrast, the characteristics of the stages which I have designed. In Fig. 17 the contacting horizontal edges 43, 44 of two ad-

5 jacent staves are rectilineal and at right angles to the side edges. In Fig. 16 the edge of the lower stave is formed with a projection 41 and the lower edge of the stave above 10 with a corresponding recess 42. The interlocking projection and recess prevent the lateral slipping, bodily, of the end portion of either stave; and consequently the upper one must rock upon a fulcrum point with a 15 tendency to form an opening between the adjacent edges. If the lower end of the upper stave can slip, bodily, around a circularly curved edge, as shown in Fig. 6, it tends to maintain a tighter joint as above described.

15 20 25 30 35 40 45 50 55 60 65 70 75 80 85 90 95 100

15 A cover 39 is shown for the structure, this cover being put in place after assembling the parts above described. It can be made in any of the ordinary ways, as of cement tiling or of sheet metal, and can be secured 20 in place as preferred.

What I claim is:—

1. The herein described concrete stave for a silo-like structure, it having relatively wide inner and outer faces, parallel rectilineal side edges and parallel curvilinear end edges, one side edge and one end edge being grooved and the other end edge and side edge being correspondingly convex, the curves which define the end edges being arcs of circles extending continuously from one side edge to the other.

2. The herein described concrete stave for a silo-like structure, it having relatively

Copies of this patent may be obtained for five cents each, by addressing the "Commissioner of Patents, Washington, D. C."

wide inner and outer faces, parallel rectilineal side edges, one rounded cylindrically and the other grooved correspondingly cylindrically and two parallel curvilinear end edges, the curves which define the end edges being arcs of circles extending continuously from one side edge to the other, one end edge being rounded transversely to the wide faces, and the other end edge being correspondingly grooved.

3. A concrete stave for a silo-like structure having parallel curvilinear end edges, the curves which define said edges being arcs of circles extending continuously across the stave whereby if it is out of vertical alinement the end portion of an adjacent stave can slip in circular transverse paths, and having one side edge which is longitudinally grooved and a side edge parallel to that aforesaid and convex to correspond to the groove aforesaid, whether either side edge may be loosely fitted with the side edge of an adjacent stave while in overlapping relation therewith and while slightly out of vertical alinement, and the stave also having on its inner face seaming grooves at the corners of the wide faces and of the side edges to permit the admission of cement to seal the crevices when the side edges are not tightly fitted.

In testimony whereof I affix my signature.

JONAS GROSSNICKLE.

It is hereby certified that in Letters Patent No. 1,314,644, granted September 2, 1919, upon the application of Jonas Grossnickle, of North Manchester, Indiana, for an improvement in "Silos," errors appear in the printed specification requiring correction as follows: Page 1, line 22, for the word "stay" read *stave*; page 4, line 54, claim 3, for the word "whether" read *whereby*; and that the said Letters Patent should be read with these corrections therein that the same may conform to the record of the case in the Patent Office.

Signed and sealed this 7th day of December, A. D., 1920.

[SEAL.]

L. B. MANN,

Acting Commissioner of Patents.
